ABSTRACT OF THE DISCLOSURE

A triggering device or self-arming switch which is operable in response to change in an ambient physical variable to initiate one or more operations. The device can be used as a self-arming barometric actuated switch, arranged to trip or move a switch arm at different atmospheric pressures for the purpose of closing at predetermined different altitudes, different circuits.

This invention relates to a triggering or self-arming device operable in response to change in an ambient physical variable to initiate one or more operations.

Triggering devices responsive to change in atmospheric pressure have been used on rockets and on parachutes apparatus to deploy a parachute canopy as the rocket descends after having reached it apogee. It is a primary object of the present invention to provide a triggering device or self-arming altitude operated switch which is responsive to ambient physical change for the purpose of initiating one or more other operations.

It is an object of this invention to provide a self-arming barometric actuated switch arming device which includes a casing structure so constructed and arranged as to trip a switch arm at different pressures as the device is descending through the atmosphere, for the purpose of setting off at predetermined altitudes different operations such as the closing of different circuits.

It is an object of this invention to provide a triggering or self-arming device operable in response to changes of ambient physical variables to initiate one or more operations, and which device operates to perform said operations incidental to change in atmospheric pressure, change of the humidity, changes of temperatures or in underwater operations where the device can be arranged to arm itself upon increase of pressure and to initiate an event upon a subsequent decrease in pressure.

It is a further object of this device to provide a triggering or self-arming device which can arm itself at a high altitude whereby during descent it will perform operations at different lower altitudes, such as to successfully initiate deployment of a small drogue or pilot parachute canopy and later deployment of a main parachute canopy.

Other objects and advantages of this invention will be apparent during the course of the following detailed description.

FIGURE 1 is a top plan view of the device, showing the top cover end.

FIGURE 2 is a cross-section taken on the line 2—2 of FIGURE 1 and more particularly showing the device as the details would appear at ground level with its trip lever held in an inoperative position and showing aneroid capsule means to arm and control the device.

FIGURE 3 is a cross-section view taken on the line 3—3 of FIGURE 1, showing the device as its details appear at ground level and with the trip lever or switch held inoperative.

FIGURE 4 is a plan view of the details of the device

with the cover removed and the trip lever held inoperative.

FIGURE 5 is an enlarged cross-section taken on the line 5—5, shown in FIGURE 4, of one circuit which may be closed by the device for performing an operation.

FIGURE 6 is a cross-sectional view of the details shown in FIGURE 2, but showing the aneroid capsules expanded by increase in pressure for the purpose of tripping a switch arm and allowing it to move to a position for closing an electric circuit, to perform some operation.

FIGURE 7 is a plan view of the details as they appear in FIGURE 6, showing the switch arm in position for closing an electric circuit.

FIGURE 8 is a cross-sectional view of details appearing in FIGURE 2, but with the trip lever or switch arm in position to enable closing of another electric circuit upon further altitude descent for the purpose of closing a second electric circuit and initiating another operation.

FIGURE 9 is a plan view of the details appearing in FIGURE 8 showing the trip lever or switch arm in position to close a second electric circuit at a lower altitude.

In the drawings wherein for the purpose of illustration is shown a preferred embodiment of the invention and in which similar reference characters designate corresponding parts throughout the several views, the letter A

25 may generally designate the self-arming altitude operating switch. It preferably includes a casing structure 10 which includes an annular or other shaped wall 11 having a bottom closure 12 and a top cover closure 13. The wall 11 is provided with an external annular flange 14 against which the bottom closure 12 is positioned and bolted thereto as at 15. A gasket 16 may seal the mounting of the bottom closure 12 upon the wall 11. The casing 10 further includes another annular flange 20 to which the top closure 13 is bolted at 13a. A gasket 22 is provided to seal the connection of the top closure 13 upon the wall 11. The wall 11 defines a chamber between the closures 12 and 13 which may be subdivided into an upper chamber 23 and lower chamber 24 by an annular internal flange 26. The annular flange has an opening 27 therethrough to communicate the chambers 23 and 24.

The bottom closure 12 is intended to support a barometric motor 30 operated by changes in pressure of surrounding atmosphere. It consists of a lower aneroid capsule 31 and an upper aneroid capsule 32. They are centrally connected together at 33. The capsules operate the same as any aneroid capsule, expanding and contracting according to varying atmospheric pressures. The lower capsule 31 is provided with a central screw threaded stud

34 which may be bolted by a nut 35 to the bottom closure 12, thus positioning the two capsules in the chamber 24 for vertical expansion and contraction. Preferably the screw threaded stem 34 is screwed into the wall 12 and the nut 35 acts as a lock nut. On top of the upper capsule 32 and centrally thereof is located an upstanding central stem or stud 36, shown in FIGURE 3, upon which is positioned an inverted rigid cap or collar member 37 which may support a clamping screw 38 in order to clamp the same to stud 36 at the proper operating height. The rigid cap or collar member 37 controls the position of a switch arm or lever, to be subsequently described. It is provided with centrally positioned upstanding radially reduced portion 40 defining an annular upwardly facing shoulder 41. Its upper surface 42 is flat and positioned at right angles to the axis of movement of the barometric motor. The stepped stud or collar 37 controls the position of a switch arm, to be subsequently described, under influence of its position as determined by the barometric motor. A trip lever 50 of insulation material is pivotally mounted on a pin 51 which is secured as by a bottom head portion 52

70 upon the flange 26. It is located on a vertical axis. This

enables the arm 50 to swing horizontally in the upper chamber 23. A spring 54 is secured by screws 55 as shown in FIGURE 4, to the outer side of the lever 50; the spring 54 being bowed and engaging the internal wall of the chamber 23, as shown in FIGURE 4, for the purpose of normally urging the switch lever 50 inwardly so it may move from the cocked position shown in FIGURE 4 to its most advanced position as shown in FIGURE 9.

Referring to FIGURE 3 it will be noted that the pivot pin 51 of the trip lever or switch arm 50 does not extend the entire distance through the arm 50. A pointed screw 60 is screwed into the top cover 13 and held in position by a lock nut 61. The point of the screw designated at 62 is located in the pivot hole of the arm 50. Thus, the switch arm 50 pivots about the point of the screw as well as upon the pin 51. The switch arm 50 is slotted at 64 to provide some resistance against the pressure of the pointed screw 60. Of course, the pressure of the screw 60 is adjusted to prevent movement of the trip lever in one direction perpendicular to the plane of intended movement while producing the minimum pivotal friction.

As shown in FIGURE 2 a supporting block 65 is mounted upon the flange 26 by means of a clamping screw or bolt 66. The head of this screw 66 also secures an elongated leaf spring 67 in position upon the block. This spring extends radially across the casing 10 and is located in the upper chamber 23. The spring 67 has secured to it, by means of screws of bolts 70, a catch or stop 71. The leaf spring 67 and stop 71 constitute an arming element or arrangement. The leaf spring 67 allows movement of the stop 71 in a direction towards and away from the switch arm. The purpose of this stop 71 is to engage, at its end edge, the arm 50 to hold the latter in an inoperative position, as shown in FIGURE 2. The free end of the leaf spring 67 is bowed or bent upwardly at 73 and bears against the under surface of the top cover 13 of casing or housing 10 to prevent bounce of spring 67, which might accidentally arm the device. The trip lever 50 can be pivoted to latch behind the edge of stop 71, shown in FIGURE 2, for the purpose of holding it in a disarmed condition.

For the purpose of tripping the catch 71 and moving the leaf spring 67 a stem 75 having a screwed portion 76 is threaded through the spring 67 and catch 71 the same having the lower end thereof in position to be engaged by the shoulder 41 of the rigid member 37. The stem or member 75 is locked in position by nut 78. It can be vertically adjusted so that the rigid member 37 of the barometric motor can actuate it for disarming the switch arm 50 at the proper time. The barometric motor moves the rigid member 37 against the stem 75 just before the barometric motor becomes fully expanded. At the outer movable end of switch arm or trip lever 50 there is provided a contact bridging spring 80 secured by a screw or bolt 81 in position. It is adapted to bridge contacts mounted upon the casing 10.

FIGURES 2 and 3 of the drawings show the capsules 31 and 32 of the barometric motor collapsed so that the rigid member shoulder 41 is spaced from the stem 75. This permits the barometric motor capsules to expand and the stud 37 to be elevated from the position shown in FIGURE 2. After the spring 67 has been lifted to release the stop 71 from holding the switch arm 50, the spring 54 will move the switch arm 50 to engage the stud or collar 37 at its larger diameter portion. The device is then armed.

The top closure 41 of the housing 10 is provided with a vent opening 90 to provide access of the atmosphere to the interior of housing 10. A tube 91 is connected to the cover 13, as shown in FIGURE 3, having a passageway 92 therein communicating with the vent opening 90. This gives protection to the vent opening and enables the device to operate in response to atmospheric pressure. When not in use the vent opening can be closed by a bung 93, shown in FIGURE 3, in dot and dash lines, to prevent

ingress of dust and dampness to the chambers 23 and 24.

The operation of the device follows:

The top cover 13 is normally held closed by the counter-sunk screws 13a. It is removed and the trip lever 50 is pivoted until it latches behind the edge of the catch 71 of the arming element. The top cover is then replaced.

Assuming the device A is used in connection with rocket or other mechanisms, after being projected into the air, when atmospheric pressure is decreased the capsules expand until the edge 41 of stud 37 bears against stem 75 of the arming element. Continued expansion of the capsules pushes the catch 71 out of engagement with the trip lever or the switch arm 50 allowing the latter to be urged by spring 54 against the larger diametered portion of the rigid member 37. The device is now armed and this arming is preferably arranged to occur just before the capsules 31 and 32 reach the limit of expansion.

With increasing ambient pressure the capsules 31 and 32 begin to collapse. This moves the rigid member 37 downwardly until the trip lever 50 moves from the larger diametered portion of the collar 37 and engages the reduced end 40 of this member 37 at a location above the shoulder 41. At the end of this movement of the collar 37, the trip lever 50 bridging contact 80 engages the pair of contacts 100 located on the housing 10 in the chamber 23. This closes an electrical circuit for the performance of some operation or other event. Further increase in ambient pressure causes further collapse of the barometric motor capsules until the trip lever 50 slips off the collar 37 and moves over the top surface of the rigid member 37 to the position shown in FIGURE 8, whereupon the bridging contact 80 of the switch arm engages or wipes across a second pair of contacts 101 and closes a second electrical circuit to perform another operation or initiate another event.

It should again be noted that at atmospheric ground pressure the barometric motor 30 is in collapsed position, as shown in FIGURE 2, with the catch 71 engaging the switch arm 50 to hold it inoperative. During rise of the device in the atmosphere to a lower pressure the capsules of the barometric motor 30 expand to a point where the catch 71 releases the switch arm 50. The latter can then move to engage the larger diameter portion of the barometric control member 37 as above described and thereafter the device functions as above described for the closing of a plurality of circuits, at different altitudes, for the initiation of a plurality of operations or events.

In FIGURE 5 is shown an insulation plug 102 with connected wires 103 arranged so that as the switch arm contact 80 engages the pair of contacts 100 or 101 the same will close one or more electric circuits.

Various changes in the shape, size and arrangement of the parts may be made to the form of invention herewith shown and described, without departing from the spirit of the invention or the scope of the claims.

I claim:

1. A triggering device comprising a support, a movably mounted control means on said support, motor means on said support actuated by an ambient physical variable armoring means to releasably maintain said control means inoperative, said motor means having means thereon to actuate said arming means for releasing said control means at a predetermined ambient physical change to perform a first operation and subsequently a second operation at an another and different ambient physical change.

2. A triggering device comprising a support, motor means mounted on the support and movable in response to a change in an ambient physical variable, a rigid member operatively connected to said movable motor means to move in opposite directions upon changes of the ambient physical variable, a movable member mounted on the support for movement in a direction transverse to the direction of movement of said rigid member, an arming element mounted on the support serving to hold the movable member against movement,

in an inoperative position, the arming element upon movement of said rigid member in one direction being displaced to allow said movable member to bear on the rigid member for arming the device, and means on the rigid member to control the position of the movable member at different changes in ambient physical variables for performance of a plurality of different operations.

3. In a self-arming altitude operating switch device the combination of a frame structure, a barometric motor mounted upon the frame structure having a vertically movable member provided with stepped portions which are vertically stepped, a switch arm movably mounted upon said frame for movement in a direction transverse to the movement of said stepped member, spring biasing means normally biasing said switch member in the direction of said stepped member, arming means mounted on the frame to normally maintain said member out of the path of engagement with the stepped member, means carried by the arming means for engagement by the stepped member to release the switch arm upon expansion of the barometric motor, said frame having a plurality of relatively insulated contacts thereon at different locations adapted to be engaged at different times by the switch arm, the stepped portions of said movable member being such that at different positions of movement of the barometric motor the steps will release the switch arm for causing successive engagement of the contacts to successively close different electric circuits.

4. A self-arming altitude operating switch device comprising a housing, barometric aneroid capsule means mounted in said housing having a movable end. A stud mounted on said movable end for movement therewith, a switch arm movably mounted on the housing for movement in a direction transverse to the movement of said stud, holding means to normally hold the switch arm inoperative and out of the path of said stud, said holding means being engageable with said stud upon inflation of the aneroid capsule means to trip the same and release the switch arm for contact with the stud.

5. The device of claim 4 in which a plurality of sets of contacts are mounted at different locations on its housing in the path of travel of the switch arm, said switch arm having a bridging contact adapted to engage said contacts at different intervals during movement of the switch arm, and said stud having relatively stepped portions adapted to be engaged by the switch arm to initiate the closing of different circuits at different times.

6. The device of the claim 5 in which spring means

normally biases the switch arm to move into the path of travel of the stud.

7. The device of claim 6 in which means is provided to prevent release of the switch arm holding means except under influence of movement of the stud upon expansion of the aneroid capsule means.

8. The device described in claim 6 in which the switch arm is pivoted and in which the housing is provided with means to prevent movement of the switch arm transverse to its normal pivotal movement.

9. In a self-arming altitude operating switch device the combination of a housing having a chamber therein, an atmospheric pressure actuated barometric motor having a movable portion, means on the barometric motor movable portion defining a plurality of shoulders relatively stepped, located at different distances from the axis of movement of the barometric motor movable portion, a pivoted switch arm mounted on the housing, arming means normally releasably holding the switch arm in an inoperative position, spring means normally biasing the switch arm to move in the direction of said stepped portion of the barometric motor, and means on the holding means adapted to be engaged by the movable end of the barometric motor to release the switch arm against said stepped portions.

10. The device of claim 9 in which the housing at different locations in the path of travel of the switch arm has mounted thereon relatively spaced pairs of contacts, and a bridging contact carried by said switch arm for successively bridging said pairs of contacts at different atmospheric pressures controlled positions of said stepped portions to successively close different circuits.
